BEDSIDE RAIL

Morton I. Thomas, Monroe, N.Y.
(125 South St., Passaic, N.J. 07055)

Filed Aug. 5, 1971, Ser. No. 169,598

Term of patent 14 years

Int. Cl. D6—06

U.S. Cl. D6—198

FIG. 1 is a side elevational view of bedside rail showing my new design;

FIG. 2 is a top plan view thereof.

I claim:

The ornamental design for a bedside rail, substantially as shown.
